UNITED STATES PATENT OFFICE.

MARTIN PANIAN, OF EVELETH, MINNESOTA.

COBBLER'S CABINET.

1,387,303.

Specification of Letters Patent. Patented Aug. 9, 1921.

Application filed March 19, 1921. Serial No. 453,657.

To all whom it may concern:

Be it known that I, MARTIN PANIAN, a citizen of the United States, residing at Eveleth, in the county of St. Louis and State of Minnesota, have invented a new and useful Cobbler's Cabinet, of which the following is a specification.

This invention has reference to cabinets, and more particularly to cabinets especially designed for cobbler's use, the primary object of the invention being to provide a cabinet for retaining nails, heels or the like so that the person using the cabinet will have easy and ready access to the contents thereof.

A further object of the invention is to provide compartments for supporting rubber heels, the compartments having cut out portions providing clearances for the person's fingers using the device to facilitate the removal of the heels.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 is a front elevational view of a cabinet, constructed in accordance with the present invention.

Fig. 2 is a sectional view taken on line 2-2 of Fig. 1.

Fig. 3 is a fragmental side elevational view.

Referring to the drawing in detail, the cabinet includes end walls 5, a rear wall 6 and a bottom 7, the bottom being shown as extending beyond the front of the cabinet to provide a forward compartment 8, there being provided partitioning members 9 within the cabinet for partitioning the cabinet and compartment into sections.

The forward sections which are indicated by the reference character 10 have the front wall thereof, which is indicated at 11 formed with a plurality of recesses or cut out portions 12 providing clearances for a person's fingers to permit him to readily grip an article contained therein.

The forward sections are designed to accommodate rubber heels and to this end, it is the purpose of the inventor to secure a heel indicated at 13, to the front wall 11 of the forward compartment, the number of the heel appearing directly under the same, so that the operator may at a glance remove the proper sized heel for the work to be accomplished, the use being as follows. With the cabinet close at hand, the operator places the heel on the shoe on which he is working over the sample heel 13 which is supported by the cabinet, and locates the proper sized heel.

When the proper sized heel is located, the cobbler may by inserting his fingers in the cut out portion in the front wall of the section on which the rubber heel is supported, remove a heel which will exactly fit the shoe under operation. From the foregoing it will be seen that the use of this cabinet eliminates the necessity of removing rubber heels from their boxes to fit the same on heels of shoes being repaired, in order that the proper sized heel may be located.

The cabinet is also provided with a front wall 14 which is formed preferably of cloth, to permit the operator to readily raise the cloth and remove nails, tacks or the like, employed in shoe repairing.

In the modified form of the invention as illustrated by Fig. 3, a hinged door 15 forms the front wall of the cabinet, and is normally held in its closed position by means of the leaf spring 16 which bears thereagainst.

Having thus described the, invention what is claimed as new is:

A cabinet comprising end walls and a rear wall, a bottom member having connection with the end and rear walls, the bottom member extending beyond the front portion of the end walls to provide a compartment, partitioning members for dividing the cabinet and compartment into sections, a movable wall forming the front of the cabinet, and a front wall for the compartment.

In testimony that I claim the foregoing as my own, I have hereto affixed my signature in the presence of two witnesses.

MARTIN PANIAN.

Witnesses:

A. A. Trott,
SALLY DONNELLY.
